UNITED STATES PATENT OFFICE.

EDWARD C. HARRINGTON, OF ST. LOUIS, MISSOURI.

PROPELLER.

1,160,884.

Specification of Letters Patent. Patented Nov. 16, 1915.

Application filed February 15, 1913. Serial No. 748,673.

To all whom it may concern:

Be it known that I, EDWARD C. HARRINGTON, a citizen of the United States, residing at St. Louis, in the State of Missouri, have 5 invented a new and useful Propeller, of which the following is a specification.

This invention relates to propellers.

The object of the present invention is to provide a propeller of simple construction 10 and one which will eliminate all tendency to slip or churn and therefore the maximum efficiency will be realized.

With the foregoing and other objects in view which will appear as the description 15 proceeds, the invention resides in the combination and arrangement of parts and in the details of construction hereinafter described and claimed, it being understood that changes in the precise embodiment of the 20 invention herein disclosed, can be made within the scope of what is claimed, without departing from the spirit of the invention.

In the drawings accompanying this specification and forming a part thereof, the 25 preferable form of my invention is illustrated, in which:—

Figure 1 is a plan view of my improved propeller. Fig. 2 is a side view thereof or a view similar to Fig. 1 in which the propeller 30 has been rotated through 90 degrees. Fig. 3 is an end view thereof. Fig. 4 is a cross sectional view of Fig. 2 on the line A—A. Fig. 5 is a plan view of the blank from which the propeller is formed.

Referring to the drawings in which similar reference numerals designate corresponding parts throughout the several views, A represents the propeller shaft or hub which in the present instance is provided with a 40 suitable slot or groove extending centrally thereof and into which is adapted to fit the metallic blank B as illustrated in Fig. 5. The metallic blank B is circular in outline and is formed of sheet metal of sufficient 45 thickness to lend the required strength and rigidity to the propeller when the same has assumed its final form. It is to be noted however that the propeller may be made of cast metal without departing from the spirit 50 of the invention. The said circular blank B is provided with a slot C therein which is in alinement with the propeller shaft A and extends from the center of the blank to the circumference thereof.

55 In the forming of my improved propeller from a sheet metal blank such as illustrated

in Fig. 5 the edges of slot C of the upper and lower blades 1 and 2 are first bent tangential to the line of the propeller shaft A and extend therefrom in a curve such that the 60 points 4—4 at the outer extremities of the line of division C between the blades would when connected with the extremity of the propeller shaft which extends to the center of the propeller blade as illustrated in Fig. 65 5, define an angle of approximately 90 degrees such as is designated in Fig. 2. The blade 1 is then twisted or turned to form a continuous curve from the point 3 upon the circumference of the blank through approximately 180 degrees to a point diametrically 70 opposite therefrom as at 4. The same pitch is given to each of the blades 1 and 2 and the result thereby obtained is a propeller with a varying pitch and therefore one 75 which will give the maximum efficiency in use and will eliminate all tendency to churn or slip.

From the foregoing it will be apparent that my improved propeller may be cast in 80 the form illustrated in Fig. 2 or formed of a blank as illustrated in Fig. 5 and bent to the desired configuration. Each blade will therefore have a true and constantly varying pitch from the point 3 on the circumference 85 where the propeller shaft intersects the propeller proper and from this point to the outerbent ends 4 of the blade will be a constantly varying pitch which will produce an efficient propeller, the circumference of each 90 blade turning through approximately 180 degrees and the edges of the cut slot C in the blank are bent tangential to the line of the propeller blade shaft and form an angle therewith of approximately 45 degrees, and 95 include between their edges an angle of approximately 90 degrees.

It is to be understood that I do not wish to limit myself to the slotted shaft construction as the same may be varied as illustrated 100 in Fig. 4 in which the blades of the propeller are made integral with the hub.

Having thus fully disclosed the construction of my improved propeller, what I claim to be new and original with me is:—

1. A propeller comprising in blank a circular plate, said plate cut along a radial line, a propeller hub secured to said plate extending radially thereof and in alinement with the said cut, the said blank being bent 110 to bring the ends of said cut in a direction perpendicular to the plane of the blank de-

- fining therebetween an angle of substantially 90 degrees taken with the center of said blank as the apex of the angle, the two semi-circular portions of the blank lying upon opposite sides of the cut and propeller hub and being bent to form blades of specific curvature, the said curvature being such as would be obtained by holding the extremities thereof stationary and rotating the hub through substantially 180 degrees.
2. A propeller comprising a hub, two blades carried thereby, each blade being formed from a semi-circular blank twisted

through substantially 180 degrees, and with the adjacent extremities of the blades bent in opposite directions to form an angle of substantially 90 degrees therebetween taken with the end of the hub as the apex of the angle.

In testimony that I claim the foregoing as my own, I have hereto affixed my signature in the presence of two witnesses.

EDWARD C. HARRINGTON.
